UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Application filed October 7, 1926, Serial No. 140,080, and in Great Britain April 7, 1926.

My invention relates to rail anchors and particularly to rail anchors of the one-piece type adapted to grip opposite edges of the base portion of a railroad rail.

5 The principal object of the invention is to provide, in an anchor of the above character, an improved arrangement and construction of the rail-gripping jaws whereby the anchor is maintained in its normal gripping position 10 on the rail by reason of an initial stress to which the device is subjected during its application to a rail, and whereby the engagement of one of said jaws with the rail is such that the pressure exerted on the said jaw by 15 the creeping movement of the rail tends to move the anchor transversely of the rail to increase the grip of the device on the rail.

Another object is to provide an improved anchor of the one-piece torsion yoke type in 20 which the yoke is so constructed as to effect an initial shackle grip on the top and bottom surfaces of the rail base by reason of an initial torsional stress to which the anchor is subjected during its application and to 25 provide an arrangement of jaws whereby the torsion of the yoke is partially relieved when the anchor device assumes its rail gripping position.

Another object is to provide, in a rail 30 anchor of the above general character, an arrangement of jaws whereby a relatively wide jaw portion is provided at one end of the anchor device. In this connection I also contemplate the provision of improved constructions whereby the end of the anchor adjacent 35 the relatively wide jaw is formed with a tie-abutting portion which may, if so desired, bear against the vertical face of a cross-tie adjacent one side of the rail so as to hold the major portion of the yoke in spaced relation 40 to said tie.

The invention has for further objects such other improved constructions in rail anchors as will appear from the following description 45 of the several embodiments shown in the accompanying drawings, and the features of novelty will be set forth in the claims.

The invention is illustrated in several preferred embodiments in the accompanying drawings wherein

Fig. 1 is a plan view of the base portion of a railroad rail showing a rail anchor, con-

structed in accordance with my invention, applied thereto.

Fig. 2 is a face view of the anchor device 55 illustrating the manner in which it is applied to the base portion of a railroad rail and showing the base portion of the rail in section.

Fig. 3 is an end view of the anchor taken 60 from the left of Fig. 2.

Fig. 4 is an end view showing the end elevation of the anchor device and is taken from the right hand end of Fig. 2.

Fig. 5 is a view in perspective of the anchor device removed from a rail, showing the 65 normal torsional set of the anchor.

Fig. 6 is a plan view similar to Fig. 1, illustrating a modified form of the invention applied to the base portion of a railroad rail. 70

Fig. 7 is a face view of the embodiment shown in Fig. 6.

Fig. 8 is an end view taken from the right hand end of Fig. 7.

Fig. 9 is an end view of the opposite end 75 of the embodiment shown in Figs. 6 to 8 inclusive.

Figs. 10 and 11 are plan and end views, respectively, of a rolled metal bar from which the one-piece anchor of the type 80 shown in Figs. 6 to 9 inclusive is sheared.

Fig. 12 is a plan view illustrating a modified embodiment of the invention and

Figs. 13 and 14 are views similar to Fig. 12 illustrating further modified embodiments. 85

Referring first to the embodiments shown in Figs. 1 to 5 inclusive of the drawings, wherein I have shown one embodiment of my invention formed from a flat metal blank. 90 The upper portion of the blank is cut away to provide a recess 10 adapted to receive the base portion 11 of the rail. The recess is so formed as to provide a short jaw 12 and a long jaw 13 adapted to project over and bear against the upper inclined surfaces of the rail base at opposite sides of the rail base. The long jaw is preferably bent outwardly from the body of the yoke so that the effective width of the recess 10 underlying this jaw can be increased by tilting the anchor about an axis extending longitudinally of the yoke so as to elevate the extremity of the long jaw. This means of in-

creasing the effective width of the said recess is utilized, as will be described hereinafter, during the application of the device to a rail. The long jaw is preferably bent outwardly from the body so that, as viewed in plan in Fig. 1, it stands at an angle of approximately 45 degrees with respect to the body. Under such conditions, the lower edge 14 of the end of the jaw stands at a corresponding angle with respect to the longitudinal edge of the rail base. With the jaw 13 disposed at the above mentioned or other suitable angle, the lower edge 14 of the jaw may be brought to bear flatwise against the inclined upper surface of the rail base by rocking the end of the jaw downwardly toward the rail base. With this construction the engagement of the jaw 13 is confined to the edge contact 14, the other portion of the lower edge of the jaw 13 being formed so as to provide a clearance between the jaw and the upper surface of the rail base. The body portion of the yoke adjacent the long jaw is formed with a shoulder 15 which snaps over the lower corner of the rail base when the anchor is moved to its operative position.

The short jaw 12 at the other end of the anchor is formed with an inclined lower edge 30 which inclination is slightly less than the inclination of the upper surface of the rail base. The vertical dimension of the portion of the recess 10 underlying this jaw is preferably such that the normal crushing down 35 of the end of the jaw during the application of the anchor will permit the inclined bearing surface of the jaw and the upper edge 16 of the yoke body to take a tight wedging fit on the top and bottom surfaces of the rail. The jaw 12 is preferably offset 40 with relation to the body of the yoke so that the gripping surface 17 of the short jaw will normally be out of vertical alignment with the upper edge 16 of the yoke. With this construction, I obtain an effective increase 45 in the width of the bearing surfaces 16 and 17, longitudinally of the rail. In this connection it will be seen from Fig. 4 of the drawings, that the application of force tending to swing the bottom portion of the yoke 50 in a direction away from the cross tie 18 will tend to force the forward edge 19 of the jaw 12 and the rear edge 20 of the yoke body into tight shackle engagement with the 55 top and bottom surfaces, respectively, of the rail base.

The jaw 12 is preferably offset along a line longitudinally of the body and projects outwardly from the side of the body opposite to that from which the long arm projects. The body of the yoke is given a slight torsional set so that the jaws 12 and 13 will normally be at an angle to each other on opposite sides of the body when the anchor is free of the rail.

In applying the yoke to a rail, the jaw 13 is first hooked over one edge of a rail base as indicated in dotted lines in Fig. 2. The anchor may be applied in this position without straining the jaw 13, by simply tilting the lower edge of the yoke away from the cross-tie, thereby elevating the extremity of the long jaw in a manner to increase the effective width of the rail-base receiving recess. The jaw 13 and the upper edge of the body portion of the yoke may then be brought into gripping engagement with the top and bottom surfaces of the rail base by tilting the yoke in the opposite direction, to the position shown in Fig. 4. The jaw 80 end 12 of the yoke may be raised so as to clear the upper edge of the opposite edge of the rail base. During this movement the jaw 13 is forced downwardly on the top of the rail base and the body portion of the yoke is stressed by a twisting movement of the jaw 12 of the yoke. After the yoke is twisted to such position as will permit the offset jaw 12 to be hooked over the base flange of the rail, the entire yoke is moved 85 bodily transversely of the rail, that is from the dotted line position of Fig. 2 to the full line position. When the yoke is moved to the full line position, the shoulder 15 snaps up over the lower edge of the rail base so as to lock the yoke against movement in the direction from which it was driven. The torsional stress of the yoke is partially relieved by the movement of the yoke transversely of the rail to its applied position. 90 The relief is effected, as will be seen from the drawings, by the downward movement of the long jaw on the inclined surface of the rail base. The angular position of the jaws with relation to each other is, preferably, such that the yoke is stressed a greater degree than is relieved by the downward movement of the long jaw. The torsional stress remaining after the anchor is applied to its operative position tends to rock the jaw 12 in the direction from which it was twisted and thereby effects a shackle grip of the jaw 12 and the upper edge of the yoke body upon the top and bottom surfaces, respectively, of the rail base. This torsional grip, however, serves to maintain the yoke in its applied position. Any movement of the anchor in a direction to remove it from the rail forces the long jaw upwardly on the inclined surface of the rail base and thereby increases the torsional stress on the yoke member. The edge engagement 14 of the jaw 13 normally has a biting engagement with the inclined surface of the rail base. This biting engagement, together with the angular position of the edge 14, with relation to the edge of the rail base, tends to increase the grip of the anchor on the rail when the rail is subjected to creeping pressure. This increased grip is effected by rea- 100 105 110 115 120 125 130

son of the fact that the groove or furrow produced in the top surface of the rail base by the biting edge 14 of the long jaw exerts a cam action against the edge 14 of the jaw so as to shift the anchor bodily toward the right of Fig. 2. The transverse shifting of the anchor to the right of the drawing forces the jaw 12 into tighter gripping engagement with the opposite edge of the rail base. During the transverse shifting movement of the anchor, under the influence of the creeping movement of the rail, the edge 14 of the long jaw will move downwardly on the inclined surface of the rail base and by such movement will extend the groove or furrow along the dotted lines indicated by the reference character 21 in Figs. 1 and 4. In Fig. 4 of the drawing I have shown the end of the anchor moved to such an angle as to bring the edge 14 of the jaw 13 flat against the inclined surface of the rail base. In addition to the tendency which the yoke has to move transversely of the rail during the presence of creeping pressure, the pressure of the lower portion of the yoke against the tie tends to increase the shackle grip of the jaws 19 and 20 (Fig. 3) upon the top and bottom surfaces of the rail base.

In Figs. 6 to 11 inclusive, I have shown a modified embodiment of anchor device. In this modification, the bearing surfaces 16^a and 17^a of the short jaw end of the anchor are arranged in vertical alignment. These surfaces, however, are somewhat wider than the thickness of the major portion of the yoke body. The increased width of the short jaw end of the anchor, in addition to providing wide bearing surfaces 16^a—17^a, provides the tie abutment which holds the major portion of the yoke away from the cross tie.

The metal blanks from which the above embodiment is made are preferably sheared from a metal bar rolled to the cross-sectional configuration shown in Fig. 11. One edge of the rolled bar, it will be noted, corresponds in thickness to the thick end portion 22 of the yoke. The width of the rolled metal bar corresponds to the length of yoke member so that the yoke blanks may be sheared transversely of the bar as shown in outline in Fig. 10. The other portions of this anchor are preferably the same as that shown in the preceding figures.

In Fig. 12 I have shown another embodiment in which the short jaw end 12^b of the anchor is offset on a vertical line 23 with relation to the body of the anchor so as to provide a tie-abutting surface 24 at one end of the anchor. This tie abutment, it will be noted, holds the long jaw end of the anchor in spaced relation with the tie.

In Fig. 13, I have shown another embodiment in which the short jaw portion 12^c is made relatively thick by bending the end

of the blank upon itself, as shown by the reference character 25. This construction provides a short jaw 12^c of double thickness.

In the modification shown in Fig. 14, the end 26 of the yoke is recessed and bent to a substantially U-shaped configuration so as to provide spaced jaws 12^d—12^d'. The spaced jaws 12^d—12^d' take a wedging fit on the rail base in the same manner as that of the preceding figure. The thickness of the yoke body of this embodiment may, if desired, be made somewhat thinner than the embodiment shown in the preceding figures.

All of the embodiments except for the special construction above noted, are made and applied to the rail in the same manner as described in connection with Figs. 1 to 5 inclusive.

While I have illustrated the invention in connection with several specific embodiments, I do not wish to limit myself to the embodiments shown and described except in so far as specific limitations are set forth in the appended claims.

I claim:

1. A rail anchor consisting of a member provided at opposite ends with jaws and adapted to be moved in the direction of its length transversely of the rail to move said jaws into their rail gripping positions, one of which jaws is bent outwardly from the body of the anchor so as to extend longitudinally of the rail in a direction away from an adjacent cross tie, and which engages at its extremity only the top surface of the rail base.

2. A rail anchor consisting of a member provided at opposite ends with jaws and adapted to be moved in the direction of its length transversely of the rail to move said jaws into their rail gripping positions, one of which jaws is bent outwardly from the body of said member so as to extend longitudinally of the rail in a direction away from an adjacent cross tie, and which engages at its end only and with a line contact, the top surface of the rail base.

3. A rail anchor consisting of a member provided at opposite ends with jaws which are moved transversely of the rail to their rail gripping positions, one of which jaws is bent outwardly from the body of said member so as to extend longitudinally of the rail in a direction away from an adjacent cross tie, and which is adapted to be rocked downwardly toward the inclined top surface of the rail base to bring the extremity only of said jaw into line contact with said inclined surface.

4. A rail anchor consisting of a member provided at opposite ends with jaws which are moved transversely of the rail to their rail gripping positions, one of which jaws is bent outwardly from the body of said

member so as to extend longitudinally of the rail in a direction away from an adjacent cross tie, and at an angle to the adjacent edge of the rail base and which is adapted to be rocked downwardly toward the inclined top surface of the rail base to bring the extremity only of said jaw into line contact with said inclined surface.

5. A rail anchor consisting of a member 10 provided at opposite ends with jaws which are moved transversely of the rail to their rail gripping positions, one of which jaws is bent outwardly from the body of said member so as to extend longitudinally of 15 the rail in a direction away from an adjacent cross tie and at an angle to the adjacent edge of the rail base, and which is adapted to be rocked downwardly toward the top surface of the rail base to move the 20 extremity of said jaw into biting contact with the top surface of the rail base.

6. A rail anchor consisting of a bar of spring metal formed at opposite ends with rail base engaging jaws arranged so that 25 after hooking one end of the anchor over one edge of the rail base, the bar has to be twisted and moved transversely of the rail to engage the other edge of the rail base; one of said jaws being formed to extend 30 longitudinally of the rail and adapted to be moved by said twisting of the bar into biting engagement with the top surface of the rail base.

7. A rail anchor consisting of a bar of 35 spring metal formed at opposite ends with rail base engaging jaws arranged so that after hooking one end of the anchor over one edge of the rail base, the bar has to be twisted and moved transversely of the rail 40 to engage the other edge of the rail base; one of said jaws being formed to extend longitudinally of the rail and adapted to be moved by said twisting of the bar into engagement at its end only with the top surface 45 of the rail base.

8. A rail anchor consisting of a bar of 50 spring metal, formed at opposite ends with rail base engaging jaws arranged so that after hooking one end of the anchor over one edge of the rail base the bar has to be 55 twisted and moved transversely of the rail to engage the other edge of the rail base; one of said jaws being formed to extend longitudinally of the rail and adapted to be moved by said twisting of the bar into line engagement at its end only with the top surface of the rail base.

9. A rail anchor consisting of a bar of 60 spring metal relatively thin with respect to its vertical dimension when applied to a rail and formed to provide rail base engaging jaws arranged so that after hooking one end of the anchor over one edge of the rail base, the bar has to be twisted and moved trans- 65 versely of the rail to engage the other edge

of the rail base; one of said jaws being formed to extend longitudinally of the rail and adapted to be moved by said twisting of the bar into a line engagement with the top surface of the rail base.

10. A rail anchor consisting of a bar of 70 spring metal relatively thin with respect to the vertical dimension when applied to a rail and adapted to lie substantially flatwise against one face of a cross tie and formed 75 to provide rail base engaging jaws arranged so that after hooking one end of the anchor over one edge of the rail base, the bar has to be twisted and moved transversely of the rail to engage the other edge of the rail base; one of said jaws being formed to extend 80 longitudinally of the rail and adapted to be moved by said twisting of the bar into biting engagement with the top surface of the rail base.

11. A rail anchor consisting of a bar of 85 spring metal formed at opposite ends with rail base engaging jaws arranged so that after hooking one end of the anchor over the 90 edge of the rail base, the bar has to be twisted and moved transversely of the rail to engage the other edge of the rail base; one of said jaws being formed to extend outwardly from the body of said member in a direction away from the cross tie, and the other of said jaws being adapted to project outwardly from said body in a direction toward said cross tie.

12. A rail anchor consisting of a bar of 95 spring metal relatively thin with respect to its vertical dimension when applied to a rail and adapted to lie substantially flatwise against one face of a cross tie; one of said 100 jaws being bent outwardly from the body of said bar to extend longitudinally of the rail base and at an angle to the longitudinal edge 105 of said base and the other of said jaws being offset laterally with relation to said bar.

13. A rail anchor consisting of a bar of 110 spring metal formed at opposite ends with rail base engaging jaws, and formed intermediate 115 said jaws with a torsional set so that after hooking one end of the anchor over one edge of the rail base, the bar has to be twisted in a direction to straighten out said torsional set and moved transversely of the rail to engage the other edge of the rail base; one of said jaws being formed to extend at an angle away from the body of the bar and in a direction extending longitudinally of the base and bearing at its end only against the top surface of said rail base; and the other of said jaws being offset with relation to the body of said bar so as to project 120 from the opposite side of said bar.

14. A rail anchor consisting of a bar of 125 spring metal formed at opposite ends with rail base engaging jaws arranged to be tightened on the rail base by movement of the anchor in the direction of its length 130

transversely of the rail, one of said jaws being disposed at an angle to the rail whereby creeping movement of the rail exerts a cam action against the end of said angular 5 jaw to move the jaw at the other end of device into tighter gripping engagement with the rail base.

15. A rail anchor consisting of a bar of spring metal formed at opposite ends with rail base engaging jaws arranged to be tightened on the rail base by movement of the anchor transversely of the rail, one of said jaws being disposed at an angle to the rail and adapted to be rocked downwardly 10 toward the top surface of the rail base to effect a line engagement at its end with the upper inclined surface of said base so that said engagement tends to groove the rail when the rail is subjected to creeping pressure 15 and whereby said groove will be formed at such an angle as to shift the rail anchor transversely of the rail to increase the grip of the device on the opposite edge of the rail base.

20 16. A rail anchor comprising a bar provided with jaws for gripping the rail base at opposite sides of the rail and maintaining

the rail base gripping position by torsional force exerted by the bar; one of said jaws being formed to engage the top surface of 25 the rail base at an angle to the longitudinal axis of the rail, whereby movement of the rail with relation to the last mentioned jaw exerts a force on said jaw tending to shift it transversely of the rail in a direction to 30 increase the grip of the anchor on the rail base.

17. A rail anchor consisting of a bar of spring metal formed at opposite ends with rail base engaging jaws arranged so that 35 after hooking one end of the anchor over one edge of the rail base, the bar has to be twisted and moved transversely of the rail to engage the other edge of the rail base whereby the torsional force of said bar, when 40 in its applied position, effects a shackle grip of one of said jaws on the top and bottom surfaces of the rail base, and whereby the 45 creeping pressure of the rail against the other jaw tends to shift the anchor transversely of the rail in a direction to increase 50 the grip of the device on the rail.

HAROLD G. WARR.
